Primary Examiner — Lisa Lichtenstein(74) *Attorney, Agent, or Firm* — Fitch, Even, Tabin & Flannery**CLAIM**

The ornamental design for a fan grille, as shown and described.

DESCRIPTION

FIG. 1 is a perspective view of a fan grille with our new design; and,

FIG. 2 is a front elevational view of the fan grille of FIG. 1. The broken lines showing a fan housing and stand are included for the purpose of illustrating environmental structure and form no part of the claimed design.
